UNITED STATES PATENT OFFICE

LOUIS A. BEAN, OF DENVER, COLORADO, ASSIGNOR TO IVAN L. BEAN, OF DENVER, COLORADO

DESIGN FOR A FLASH LIGHT HEAD

Application filed March 14, 1930. Serial No. 34,861. Term of patent 7 years.

To all whom it may concern:

Be it known that I, LOUIS A. BEAN, a citizen of the United States of America, and a resident of the city and county of Denver, Colorado, have invented a new, original, and ornamental Design for a Flashlight Head, of which the following is a specification, reference being had to the accompanying drawings, forming part hereof.

In the drawings, Figure 1 is a front end elevation of a flashlight head, showing my new design, Figure 2 is a top plan view of the showing of Figure 1 and Figure 3 is a side elevation of the showing of Figure 1.

I claim:

The ornamental design for a flashlight head, as shown.

LOUIS A. BEAN.
